METHOD OF MANUFACTURING DISPLAYS

Fred Lawrence, Pontiac, Mich., assignor to Max O'Donnell, Pontiac, Mich.

Application June 1, 1932, Serial No. 614,834

2 Claims. (Cl. 101—129)

This invention relates to a method of manufacturing displays and has for its object to provide, in a manner as hereinafter set forth, the expeditious and convenient producing of unusually distinctive, attractive and attention directing displays, such as signs, show cards, posters, announcements, warnings, notices, or the like.

A further object of the invention is to provide, in a manner as hereinafter set forth, a thoroughly efficient and inexpensive method of producing very attractive displays for use as advertising and other purposes.

15 A further object of the invention is to provide, in a manner as hereinafter set forth, a method for the purpose referred to including in so removing a display former from a carrier, on which the display is completed, to prevent any possibility of impairing the appearance of the completed work.

29 To the above ends essentially, and to others which may hereinafter appear, the invention consists of a method of manufacturing displays which falls within the scope of the invention as claimed.

25 The drawings illustrate by way of example one form of an apparatus capable of being employed when carrying out a method, in accordance with this invention for manufacturing displays.

In the drawings;

30 Figure 1 is a plan view of the apparatus and with the latter arranged in position when carrying out the second, third and fourth steps of the method.

Figure 2 is a plan view of the apparatus and with the latter arranged in position when carrying out the fifth step of the method to complete the display.

Figure 3 is an end view of the apparatus and with the latter in position at the completion of the sixth step of the method.

Figure 4 is a plan view of the apparatus and with the latter in position at the completion of the final step of the method.

49 tus in plan illustrating a modified form of a completed display made in accordance with the method.

The form of apparatus, illustrated by way of example which is capable of being employed 50 when carrying out the method, includes a rectangular supporting element 1 for the work and a rectangular removing element 2 for the display former or formers. The elements 1, 2 are hinged together at one side, as at 3 and element 2 is 55 arranged to be moved to and from superposed

relation with respect to element 1. The elements are of like form. Element 1 includes a section 4 in the form of a casing of non-conducting material having arranged therein a flat section 5 of any suitable construction capable of being magnetized. The work is to be mounted upon section 5. Element 2 includes a section 6 in the form of a casing of non-conducting material having arranged therein a flat section 7 of any suitable construction capable of being magnetized. The display former or formers are removed from the work by section 7. Leading to and electrically connected to the section 7 of element 2 are circuit connections 8, 9. Leading to and electrically connected to the section 5 of element 1 are circuit connections 10, 11. Power line circuit connections are indicated at 12', 13'' and which lead from a source of energy, not shown. The circuit connections 8, 9 are electrically connected to posts 8', 9' respectively. The circuit connections 10, 11 are electrically connected to posts 10', 11' respectively. The circuit connections 12', 13'' lead to posts 12'', 13''' to which the blades 14' of a switch 15' are hinged. The arrangement referred to provides for selectively energizing sections 5, 7 independently of each other. The apparatus employed may be of the form as shown in my application filed June 1, 1932, Serial Number 614,833, but it is to be understood that any form of apparatus including a pair of sections capable of being energized or magnetized may be used when carrying out the method.

The first step of the method consists in coloring that face of a display carrier or sign base 12 which is to be exposed. The carrier will consist of a thin web of any suitable material, such as paper, fabric, cardboard or metal. The colored exposed face of carrier 12 is indicated at 13 and parts of such colored face provides a colored display when the latter is produced. The apparatus at this time is to be extended to the position as shown in Figure 1, that is to say elements 1 and 2 are arranged in righted position with respect to each other. The carrier 12 with face 13 exposed is then placed flatwise upon section 5 of element 1 which constitutes the second step of the method. The means to form or create a display is termed a display former and indicated at 14. Such means is mounted at the desired point upon the colored face 13 of carrier 12. As illustrated, by way of example, a set of independent spaced solid formers 14 consisting of a series of letters to spell the word "Goods" is removably placed 110

upon carrier 12 to conceal and protect spaced portions of the colored face 13, and such portions when subsequently exposed constitute the display. The arranging of the display former 5 or formers upon face 13 is the third step of the method. Each display former is constructed of metallic material capable of being magnetized and attracted to section 5 when the latter is energized or magnetized. The fourth step of 10 the method consists in energizing or magnetizing section 5 of element 1 which will also provide for attracting the former or formers 14 thereto thereby holding the same in fixed position relative to section 5 and carrier 12, and 15 providing for the clamping of the latter stationary upon section 5.

The fifth step of the method consists in spraying the exposed part or parts of the face 13 of carrier 12 and the exposed surfaces of the former or formers 14 with a quick drying coloring composition of a color different from the color of the face 13 of carrier 12 to provide for such color of the exposed parts to be of a different color as at 13' with respect to the concealed part or parts of face 13 thereby providing the display 15 when the former or formers 14 are removed from carrier 12.

The sixth step of the method resides in de-energizing section 5 to release former or formers 30 14 and carrier 12. The seventh step consists in moving element 2 from righted position to superposed relation with respect to element 1 and to superimposed position with respect to former or formers 14. The eighth step resides 35 in energizing or magnetizing section 7 of element 2 for the purpose of attracting the former or formers 14 to the inverted face of element 2. The ninth step consists in removing the former or formers 14 from off carrier 12 by 40 shifting element 2 to righted position, while section 7 thereof is energized or magnetized, to the position shown in Figure 4 which carries the former or formers therewith. Section 7 is then de-energized to release the former or 45 formers 14. The completed work is then removed from element 1.

The elements 1 and 2 can be of a size to enable the producing of a plurality of displays at one time.

50 If desired, after the completion of the fifth step of the method and before removing the former or formers 14, a shading can be provided for the display by the application of a different

colored composition 16 adjacent portions of the former or formers 14, and in this connection see display 17 shown in Figure 5.

What I claim is:—

1. In a method of manufacturing a display, 80 positioning a display carrier upon a non-energized electro-magnetic support to expose one face of the carrier, superimposing upon the carrier a display former to conceal a part of said face, energizing said support to couple the display former therewith by attraction thereby anchoring the carrier stationary, coloring the exposed part of said face and the exposed surfaces of the display former to provide the carrier with the display, de-energizing said support for releasing therefrom the display former and carrier, inverting from righted position to superimposed relation on the released display former and over the support a non-energized electro-magnetic remover for the display former, 85 energizing the remover to couple to the inverted face thereof the display former by attraction, shifting the energized remover with the display former coupled thereto clear of the carrier and 90 from over the support and to righted position, and then de-energizing the righted remover to release the display former from said face.

2. In a method of manufacturing signs, 105 positioning a sign base upon a non-energized electro-magnetic support to expose one face of the base, superimposing upon said base in spaced relation independent letter forming elements to conceal parts of said face, energizing said support to couple said elements therewith by attraction thereby anchoring said base stationary, coloring the exposed portion of said face and the exposed surfaces of said elements to provide the base with a sign, de-energizing said support for releasing therefrom said elements 110 and base, inverting from righted position to superimposed relation on said released elements simultaneously and over the support a non-energized electro-magnetic remover for the display former, energizing the remover to simultaneously couple to the inverted face thereof, said elements by attraction, shifting the remover with the said elements coupled to said face clear of the base and from over the support and to righted position, and then de-energizing said 115 righted remover to release said elements from said face.

FRED LAWRENCE.
